CLAIM

The ornamental design for a track guide assembly, as shown and described.

DESCRIPTION

FIG. 1 is a top perspective view of a track guide assembly showing my new design;

FIG. 2 is a top view, thereof;

FIG. 3 is a bottom view, thereof;

FIG. 4 is a left side view, thereof;

FIG. 5 is a right side view, thereof;

FIG. 6 is an enlarged front view, thereof;

FIG. 7 is an enlarged rear view, thereof; and,

FIG. 8 is an exploded perspective view, thereof.

The broken lines are shown for the purpose of illustrating portions of the article that form no part of the claimed design.
